[57] CLAIM

The ornamental design for a weatherseal assembly for double hung and sliding windows, substantially as shown and described.

DESCRIPTION

FIG. 1 is a fragmentary perspective view of a weatherseal assembly for double hung and sliding windows embodying elements of my new design;

FIG. 2 is an end elevational view thereof;

FIG. 3 is a side elevational view thereof;

FIG. 4 is a top plan view thereof;

FIG. 5 is a bottom plan view thereof;

FIG. 6 is a view similar to FIG. 1 of another embodiment of my new design;

FIG. 7 is an end elevational view thereof;

FIG. 8 is a side elevational view thereof;

FIG. 9 is a top plan view thereof; and

FIG. 10 is a bottom plan view thereof.
